HEATER FOR AUTOMOBILES

William Karsel, Chicago, Ill., assignor to Stewart-Warner Corporation, Chicago, Ill., a corporation of Virginia

Application June 27, 1935, Serial No. 28,607

7 Claims. (Cl. 237—12.3)

This invention relates to heaters for motor vehicles and is particularly adapted for use with automobiles having internal combustion engines.

The objects of this invention are to provide an improved heater of the character set forth in which the heat is supplied by means of a suitable burner and is transferred to the body of the vehicle by means of a suitable fluid such as steam or the like; to provide a novel heating apparatus for automobiles, having a steam generator and a radiator, and means for transferring the steam from the generator to the radiator; to provide a heating apparatus for motor vehicles including a radiator and novel means for mounting the same on the body of the vehicle and supporting a distributing fan thereon; to provide a heater for automobiles or the like including a combustion chamber and a steam generating chamber associated therewith, and improved fuel feeding means, and means for withdrawing the gases of combustion from the combustion chamber; and to provide such other advantages and improvements as will appear more fully from the following description taken in connection with the accompanying drawings, in which.

Figure 1 is a longitudinal sectional view showing my heater as applied to the dash-board or wall of a vehicle, parts being broken away or shown diagrammatically for convenience in illustration;

Figure 2 is a sectional plan view taken on the line 2—2 of Figure 1;

Figure 3 is a bottom plan view showing the adjustable air controlling mechanism;

Figure 4 is a sectional detail taken on the line 4—4 of Figure 1 showing the circuit making and breaking device;

Figure 5 is a wiring diagram showing the circuits for the ignition device; and

Figure 6 is a sectional detail showing a modified connection between the steam generator and the radiator.

As shown in these drawings, 7 indicates generally a steam generator which is arranged adjacent to the dash-board or wall 8 of the vehicle and 9 indicates generally the heat distributing apparatus positioned within the body of the vehicle and connected to the steam generator by any suitable connecting means. Then generator 7 has a combustion chamber 10 with a plurality of baffle plates 11 for directing the movement of the gases therethrough and for transmitting heat to the walls of the cylinder or receptacle 12 enclosing the chamber. The cylinder is provided at its upper end with an intake opening 13 in which

is fitted a carburetor or gas mixer 14 of any suitable kind. This mixer is preferably provided with an adjusting screw 15 for controlling the fuel and a rotatable disc or damper 16 for controlling the air. It is also provided with an inwardly projecting pipe 17 having a plurality of small holes 18 to insure the proper mixing of the air and fuel before entering the chamber. A fuel supply pipe 19 leads from the mixer 14 to a source of gasoline or other suitable fuel supply 10 such as the carburetor 20 of the vehicle engine.

The combustion chamber 10 is enclosed or surrounded by a jacket 21 which is spaced therefrom to provide a water or steam generating chamber 22. Water is supplied to this chamber through 15 an inlet 23 having a plug 24, the upper end of the inlet terminating at a predetermined distance above the bottom of the chamber, as indicated, so that a limited amount of water may be placed in the generating chamber.

The fuel intake is preferably automatically controlled by the steam pressure. In order to do this a pipe 25 leads to a control valve 26 in the pipe 19. This control valve may be of any desired kind such as used for this purpose and preferably has a diaphragm 27 which coats with the valve stem 28 for closing the valve and also prevents steam from entering the intake pipe. The valve is preferably held in normally open position by means of a spring 29, which is positioned between 25 the diaphragm and the adjacent portion of the valve body as illustrated.

The fuel is ignited by any suitable ignition device such as a spark plug 30 which projects through an opening 31 in the combustion receptacle and is adapted to ignite the mixture therein in a well-known manner. Any suitable means such as commonly used for supplying electricity for the spark plug may be utilized, as for instance a vibrating coil or the like, but I prefer to use a circuit and controlling arrangement such as will presently be described.

The furnace or combustion chamber 10 is provided with an outlet pipe 32 which leads from the bottom thereof to the intake manifold of the vehicle engine as indicated at 33. This provides a positive suction for withdrawing the products of combustion and insures a suitable draft through the combustion chamber for drawing in the air and fuel.

My improved heat exchange devices which are located within the body of the vehicle include a radiator 34 having a hollow body portion 35 with a combined inlet and outlet connection for a hollow lug 36 which extends downwardly and out-

wardly from the lower corner of the body portion 35, the lower wall of which is preferably provided with a groove or downwardly sloping channel 37 to insure the return of the water of condensation 5 from the radiator. The lug or connection 36 has a threaded extension 38 which extends through a hole in the dash or wall 8 and which is provided with a nut 39 for drawing the shoulder or flange 40 on the connection against the opposite face of 10 the dash, thus providing a simple arrangement for fastening the radiator and associated parts in position. A pipe 41 leads from the connection 36 to a connection or hollow lug 42 extending upwardly and outwardly from the steam chamber 22 15 as shown particularly in Figure 1. The body portion of the radiator 35 also has a hollow lug or connection 43 which is provided with an air outlet or escape valve 44 to provide for the escape of air in the system when the heater is started.

20 The body portion of the radiator is provided with a plurality of encircling fins or ribs 45 which are preferably formed integrally therewith and which, together with the projecting fittings are connected with a shell or casing 46 which encloses the main portion of the radiator as shown 25 in Figures 1 and 2 but which is open at the top and bottom. It will be seen that vertical passageways 47 are thus provided around the radiator body for the circulation of air.

30 A fan motor 48 is mounted on a plate 49 which is secured to the top of the casing 46 by means of screws 50, this plate having openings 51 for the free passage of air therethrough. The fan 52 is mounted on the shaft 53 of the motor and 35 is arranged in the space between the radiator and the plate 49. The motor is supplied with current from a battery 54 or other source of electric supply through a supply wire 55 having a switch 56 therein, the opposite brush or terminal 40 of the motor being connected by a wire 57 to ground, which furnishes a return to the battery in the usual manner, as shown in Figure 5. The current supply to the spark plug 30 is preferably controlled by the motor 48. In order to do this a 45 wire 58 leads from the wire 55 to the rotor 59 of a commutator or circuit breaker, this rotor being mounted on the shaft 53 of the motor. The brush or contact 60 of the circuit breaker is connected by wire 61 with one terminal of a high tension 50 coil 62, the opposite terminal of which is grounded by means of a wire 63 or in any other suitable manner. A high tension wire 64 leads from the coil 59 to the spark plug whereby current is supplied thereto.

55 The lower end of the shell or casing 46 is closed by a plate 65 which is secured by screws 66 and which has an annular opening 67 for receiving a rotatable disc 68 having a plurality of parallel 60 openings 69. These openings are controlled by means of adjustable louvers or shutters 70 which are pivoted at 71 to the disc. The louvers have short upwardly projecting arms 72 which are connected by links or wires 73 so that they may be operated simultaneously. The end link or 65 arm 72 is connected by a link or rod 74 with a slide or thumb piece 75 which is slidably mounted in a slot 76 in the disc. The louvers or slats 70 may be adjusted by moving the thumb piece 75 and the disc may also be rotated by means of this thumb piece to direct the air in any desired 70 direction.

75 When the heater is to be used, fuel is admitted through a shut-off valve 77 in the pipe 19 and the motor 48 is started by closing the switch 56. The suction from the engine causes air and fuel to be

drawn into the combustion chamber 10 where it is ignited by the spark plug and in the particular arrangement shown current will be supplied to the plug as long as the motor is in operation. In some instances however, current may be momentarily supplied and the combustion will be continued due to the initial ignition of the fuel in the chamber. As soon as steam is generated it will pass up through the supply and return pipe 41 to the radiator and will heat the surrounding air which is driven over the same by the fan 52. The air passing over the radiator and through the housing or casing may be directed by means of adjustment of the disc 68 and the louvers mounted thereon as above described. 10 The character of the burning or flame in the combustion chamber may be noted through a sight or observation tube 78 having a transparent eye-piece 79 so that the mixture may be properly adjusted. When the steam pressure is raised 15 to a predetermined amount the pressure on the diaphragm 27 will cause the valve 26 to be closed or partly closed and thus the fuel supply will be adjusted automatically in accordance with the heat requirements. When the fan is stopped the 20 current will also be cut off from the spark plug and stop the further operation of the burner. In addition to the provision of a forced circulation through the combustion chamber, the connection with the intake manifold will also serve to 25 quickly heat the gases for the engine and thus improve the engine operation during cold weather. Furthermore, in the event of incomplete combustion in the combustion chamber any combustible gases will pass into the engine for power 30 purposes.

The modification shown in Figure 6 illustrates a slightly different arrangement for connecting the steam chamber with the radiator. In this arrangement the radiator 80 has a threaded connection 81 with an inlet opening 82 for receiving the inlet pipe 83 which is connected with the upper portion of the steam chamber 84. This threaded connection also has an outlet opening 85 which is connected by means of a return pipe 40 86 with an opening 87 in the bottom of the steam chamber 84. With this arrangement the water of condensation may pass down through the return pipe and thus insure a more rapid circulation than where it passes back through the steam 45 pipe as in the form just described.

From this description it will be seen that I provide a steam heating apparatus for automobiles in which the amount of heat furnished is independent of the heat of the engine and therefore any desired amount of heat may be readily produced and conveniently distributed in order to properly heat the body or closed part of the vehicle. While I have shown a preferred form of my invention it may be changed in the construction or arrangement of the parts in order to adapt it for different vehicles or different conditions, and therefore I do not wish to be limited to the particular arrangement herein shown and described, except as specified in the following 55 claims, in which I claim:

1. A heater for automobiles including a steam generator having a combustion chamber separate from the automobile engine and a steam generating chamber, means for supplying fuel 70 from the supply for the automobile to said combustion chamber, means for igniting the fuel in said chamber, means for exhausting the gases of combustion from the combustion chamber to the intake manifold of the engine of the vehicle, a 75

radiator mounted in the space to be heated, and means connecting the radiator with the steam generating chamber, said means comprising a conduit of sufficient cross sectional area to permit concurrent flow of steam from said generating chamber to said radiator and flow of condensate in the opposite direction.

2. The combination with an automotive vehicle having an internal combustion engine, of a substantially closed furnace, a conduit from the furnace to the fuel supply of the vehicle, an outlet conduit from the furnace to the intake of the vehicle engine, means for igniting the fuel in the furnace, a steam generating chamber operatively associated with the furnace, means for introducing a predetermined amount of water in the steam chamber, means actuated by the pressure in the steam chamber for controlling the fuel supply to the furnace, a radiator mounted in the vehicle body, a conduit connecting the radiator with the steam chamber, and a fan for circulating air around the radiator.

3. An apparatus for heating automobiles having internal combustion engines, including a combustion chamber separate from the automobile engine, means for supplying fuel from the vehicle carburetor to the combustion chamber, a mixing valve for mixing air with the fuel, means for igniting the mixture in the chamber, an exhaust pipe from the chamber to the intake manifold of the engine, a jacket surrounding said chamber, means for supplying water to the jacket, means responsive to the pressure in said water jacket to control the rate of supply of fuel to said combustion chamber, an outlet pipe leading from said jacket, a radiator connected with said outlet pipe, a casing enclosing said radiator, an electric fan for forcing air through the casing, and means for controlling and directing the movement of the air passing from the casing.

4. The combination with an automobile having an internal combustion engine and having a fuel supply of a combustion chamber separate from the automobile engine, a mixer for fuel and air connected with said chamber, a fuel supply pipe from the mixer to the fuel supply of the automobile, baffles arranged in said chamber, an outlet pipe from the bottom of the chamber connected with the intake manifold of the automobile, a spark plug for igniting the mixture in said housing, a steam generating chamber surrounding the combustion chamber, a control valve in the fuel supply pipe, means connecting the valve with the steam chamber tending to close the valve when the steam reaches a predetermined pressure, a radiator mounted in the vehicle body and comprising a receptacle having a plurality of fins projecting therefrom, means providing a passageway for steam connecting the receptacle with the steam housing, a casing enclosing said radiator receptacle, an apertured plate secured to the top of the casing, an electric fan mounted on said plate for forcing air through the casing, a disc rotatably mounted in the bottom of the casing,

openings in said disc, shutters for controlling said openings, and means for actuating said shutters.

5. The combination with an automobile having a closed body and a dash-board, and having an internal combustion engine, of a substantially closed cylinder, a generator valve connected with the intake of the cylinder, a fuel supply pipe from the generator valve to the carburetor of the engine, baffles arranged in said cylinder for deflecting the gases passing therethrough, an exhaust outlet from said cylinder, a steam chamber around the cylinder, a pressure actuated control valve for controlling the fuel supply to the cylinder, a passageway from the steam chamber to the control valve, a spark plug mounted in the cylinder, a radiator, connections from the radiator to the steam chamber, an electric fan arranged to force air around the radiator, a circuit from a source of electricity to the fan, a high tension coil, a circuit from the same source of electricity to the coil, an interrupter actuated by the motor arranged in the coil circuit, and a high tension wire from the coil to the spark plug.

6. In a motor vehicle provided with an internal combustion engine and a fuel supply for the same and having a closed body, the combination of a combustion chamber separate from the engine and arranged outside of the body, a steam generator operatively associated with the combustion chamber, a radiator mounted within the vehicle body, a conduit from the radiator to the steam generator for conducting steam from said generator to said radiator and for conducting condensate in the reverse direction, means connecting the combustion chamber with said fuel supply and with the atmosphere for supplying a combustible mixture to the combustion chamber, means for igniting said mixture, and an exhaust outlet leading from said combustion chamber to the intake manifold of the engine.

7. The combination with an automobile having an internal combustion engine, of a substantially closed cylinder, means for supplying fuel from the carburetor of the engine to the said cylinder, means for supplying air to the cylinder, an exhaust outlet from said cylinder to the intake manifold of the engine, a steam chamber around the cylinder, a pressure actuated control valve having its actuating part exposed to the steam pressure in said steam chamber for controlling the fuel supplied to the cylinder in such manner that an increase in pressure in said steam chamber will result in a reduction in the rate at which the fuel is supplied to the combustion chamber and vice versa, a spark plug mounted in the cylinder, a radiator, steam connections from the radiator to the steam chamber, an electric fan for forcing air around the radiator, a circuit from a source of electricity to the fan, and means controlled by the fan motor for supplying electricity from said source to the spark plug.

WILLIAM KARSEL.
